C. H. SCHMIDGALL,

TOOL

APPLICATION FILED FEB. 24, 1920.

Patented Dec. 12, 1922.

INVENTOR
C. H. Schmidgall,
By J. M. Weston
Atty.

UNITED STATES PATENT OFFICE.

CARL HENRY SCHMIDGALL, OF PEORIA, ILLINOIS.

TOOL.

Application filed February 24, 1920. Serial No. 361,019.

To all whom it may concern:

Be it known that I, CARL H. SCHMIDGALL, a citizen of the United States, residing at Peoria, in the county of Peoria and State 5 of Illinois, have invented certain new and useful Improvements in Tools; and I do hereby declare that the following is a full, clear, and exact description of the invention, which will enable others skilled in the art 10 to which it appertains to make and use the same.

This invention relates to improvements in that class of edge tools used for cutting metals, and known as cold chisels, and those 15 used for chiseling and working stone, though said invention is applicable to other form of tools as well.

The invention further relates to a tool of the class described, the cutting portion of 20 which may be separated from the main or handle portion when it has been rendered unfit for work after long use and restored to proper working condition and replaced in the handle, or an entirely new portion sub- 25 stituted.

The main object of my invention is to provide a tool of two main portions that are separable from one another, the cutting portion having a shank to frictionally engage 30 the other by which it is held in place, and to furnish means for positively separating the two.

Another object is that of providing a tool of the nature described having a cutting 35 portion and handle portion, held together by friction and separable from one another, and to furnish means for positively separating them, such means in no way interfering with the use of the tool and in no way acting 40 to accidentally cause separation of the parts while the tool is at work.

In the appended drawing,

Figure 1 is a longitudinal section of the complete tool in one of its forms.

Figures 2 and 3 show part of the handle portion of the tool and a detachable cutting portion, respectively, in perspective.

Figure 4 shows in perspective one of the 50 portions for assisting in the removal of the cutting portion of the tool.

Figure 5 is a side elevation of parts shown in Figure 1 produced on a much larger scale.

Figure 6 is a longitudinal section of part of the body of a tool of a modified form, 55 and

Figure 7 is a plan of the same.

A cold chisel or a chisel for stone work after being used some time loses its form and usefulness and must be reshaped, retempered 60 and ground. When this has been done a few times the tool is practically unfit for further use and must be discarded.

The purpose herein is that the handle portion of the body is a permanent part, new 65 cutting portions being supplied from a number kept on hand as often as desired in order that the tool will be kept at its highest efficiency at all times to the end that more work and better work may be done in a given 70 time. The ability to change the cutting portion as often as desired thus gives the workman the required form of an edge at any time. And combined with this is the advantage of easily removing the cutting portion 75 on occasion by an ejecting means carried in the handle portion.

1 is the body or handle portion of the form of tool shown in Figure 1, which is provided with a central longitudinal bore 2. This 80 bore opens through one end of the handle and at its other end opens into a tapered socket 3 which receives a correspondingly tapered shank 4 of a cutting member 5 which has a shoulder 6 to abut upon the end of the 85 said handle 1.

7 is a member seated in the bore 2 near the socket 3. It has a portion cut away at one side leaving a recess 8, and the point of a screw 9 in the side of the handle engages 90 therein which permits though limits the longitudinal movement of said member in the bore. The said member is further cut away at one side at its extremity remote from the socket 3 leaving but substantially one half 95 of the material and forming a recess 10 between the same and the wall of the bore 2.

Within the bore at its opposite end is a rod or bar 11 slidable therein adapted at times to project from the end of the handle as 100 shown. The opposite end of said bar or rod is spaced some distance from the member 7 and a trigger-portion 12 is interposed, being connected to the said rod by a flat spring 13 secured to each of the described portions as 105 by rivets or the like.

The said trigger portion is smaller in diameter, in one direction at least, than the bore 2, as also is the end of the bar 11 adjacent thereto to permit the attachment of 5 the spring 13 so that that portion will not create friction on the wall of said bore.

The end of the trigger adjacent the member 7 is about half the diameter of the bore or such that it and the adjacent end of the 10 member will pass one another, the spring 13 normally holding the trigger with its end opposite the recess 10.

Extending from the trigger is a finger-piece 14 which extends through a slot 15 in 15 the side of the body 1.

The shank 4 of the cutting portion 5 is held by friction within the recess 3, the shoulder 6 of the said portion abutting against the end of the handle when the shank 20 is firmly seated.

Naturally, the shank will be more or less difficult to remove from the socket 3 in consequence of which the ejecting means described is provided for easy and quick separation.

While in use since the spring 13 holds the trigger in the position illustrated, with respect to the member 7, the stroke of the hammer on the handle will merely push the rod 30 or bar 11 and the trigger inward into the recess 10 and will not have contact with the said member 7.

Now, when it is desired to remove the cutter 5, the trigger is moved backward to project the rod 11 from the handle as shown in 35 Figure 1 by means of the finger-piece 14 which, when afterward depressed, will place the end of the trigger opposite the end of the member 7, as shown in dotted lines in 40 Figure 5, whereupon a smart tap upon the end of the rod will readily eject the shank.

Figures 6 and 7 show the modified form of the tool in which 16 indicates the body or handle portion, 17 the cutter, and 18 its 45 shank.

19 is the recess for the latter and 20 is the bore corresponding to 2 in Figure 1. 21 is a member corresponding to 7 in the other figures except that it does not necessarily 50 have its inner end recessed as is said member 7. It has, however, a recess 22 within which a screw 23 extends as before.

24 is a recess in the handle 16 into which the member 21 extends. Said recess has a 55 rear inclined wall 25, and 26 is a wedge adapted to slide upon said wall and arranged to bear against the member 21. Said wedge is slotted at 27 parallel to the wall 25 and a pin 28 extends through it and the 60 handle for holding the wedge in place in the recess although permitting it to move freely.

The shank 18 holds the member 21 so that its end projects into the recess. This in turn holds the wedge raised so that it projects 65 above the surface of the body. To eject the

shank a tap upon the wedge causes that member to move into the recess and wedges the member 21 against the shank to eject it.

Minor changes may be made in my improved tool without departing from the 70 spirit of the invention or the meaning of the appended claims.

I claim:

1. A tool body having a longitudinal bore terminating in a tapered socket at one end 75 of said body adapted to receive a tool, and having an opening in its side communicating with the bore, a member lying in said bore adjacent the socket adapted for longitudinal movement and cut away at one side at its end 80 remote from the socket, a rod lying in the bore spaced at one end from the described member and adapted at its other end to be projected beyond the end of the body, a member lying in the bore between the rod 85 and the first named member opposite the opening, and a spring to hold the same normally out of alignment with the first described member opposite the cut-away side thereof and adapted by lateral pressure 90 thereon to be brought into alignment with that member whereby pressure on the rod will move all of the members to eject the tool.

2. In combination with a tool, a tool-body 95 having a longitudinal bore extending entirely through it adapted at one end as a seat for said tool, a longitudinally shiftable member lying in the other end of the bore, and parts interposed between the member 100 and the tool adapted in one position thereof, with the member wholly within the bore, to lie spaced from the seated tool, and in another position to lie snugly between said member and tool when the former is extended outside the body.

3. In combination with a tool, and a tool body having a longitudinal bore terminating at one end in a seat for said tool, of mechanism lying in said bore between the seat 110 and the other end of the body adapted in one of the positions thereof to lie in position to unseat the tool when moved longitudinally, and when in another of its positions to be ineffective to unseat the tool when 115 given such movement.

4. In combination, a cold-chisel-body having a longitudinal bore, a tool adapted to seat in said bore at one end of the body, and means in said bore including a part extending from the said body at the striking end thereof in position when engaged to be moved along the bore to engage and unseat the tool, said part when in another of its positions lying remote from the striking end 120 of the body when the tool is seated.

5. In combination with a tool body having a longitudinal bore extending entirely through it having a seat in one end to receive a tool-shank, a member slidably longi- 130

itudinally in said bore inward from the seat, there being a recess between the rear or inner end of the member and the wall of the bore, a rod lying within the bore adapted to be 5 projected from the opposite end of the body, a trigger-portion adjoining the inner end of the rod in position to contact with its inner end and having an extension projecting laterally outside the body, a flexible member 10 affixed to the sides of and connecting the rod and said trigger-portion, the latter being

normally held in line with the said recess and adapted to enter it but adapted to be moved opposite the end of the described member by pressure laterally upon said extension of said trigger-portion. 15

In testimony whereof I affix my signature in presence of two witnesses.

CARL HENRY SCHMIDGALL.
